TUNING MECHANISM

John M. Ammerman, Oak Park, Ill., assignor to
Radio Corporation of America, a corporation
of Delaware

Application June 29, 1948, Serial No. 35,769

2 Claims. (Cl. 74—10.15)

1

This invention pertains to a tuning mechanism for a radio, and more particularly to a radio tuner of novel construction and arrangement of parts requiring a reduced pressure to operate the mechanism.

It is a primary object of the present invention to provide a novel tuning mechanism which has a minimum number of movable parts, is simple in construction, economical to manufacture and utilizes a reduced pressure for purpose of operation.

Another object of the invention is to provide a tuner mechanism for sequential operation of station selection employing a core carriage assembly which carries a selector shaft with stop lobes for individual station selection and ratchet turning and stop means.

A further object of the invention is to provide a spring loaded core carriage having novel stop and adjustment means for restoring the core carriage after actuation to its next predetermined positioning means for signal reception.

A further object of the invention is to provide a spring loaded core carriage having novel means for manual and sequential tuning which may be actuated either electrically, as by a solenoid, or by a manually operable push button for sequential tuning with an independent control for tuning over a continuous range of frequency.

Further and other objects of the invention may be, and may become apparent, from a perusal of the disclosure herein. It is to be understood that while certain specific illustrations are presented, they are not to be considered as limitations except as defined by the spirit of the appended claims.

In the drawings:

Fig. 1 is a plan view of the tuner, partially broken away, showing the core carriage in position for signal reception from one of the pre-selected stations.

Fig. 2 is a side view taken along lines 2—2 of Fig. 1, showing the core carriage and sequence advancing mechanism just before completing an advancing step in the sequence.

Fig. 3 is a plan view of the tuner showing manual and electrical means connected to the operating linkage system carried by the cover of the supporting structure.

Fig. 4 is an end view of the cam shaft showing only the five cams spaced equidistant thereon in relation to one of the cam stops disposed on a cam shaft positioning screw.

Referring to the drawings, there is shown a radio tuning mechanism 11 having a supporting

structure consisting of front and rear plates 12 and 13 respectively, side plates 14 and 15 respectively, a base plate 16, and a cover plate 17. Three tuning coils in housings shown at 18, are secured to the rear plate 13 by screws 19, and have terminals for electrical connections to the associated radio receiver circuits.

Tuning cores 20 are movable within the coils, and are connected by means of tuning wires 23 and adjusting screws 22 to a core carriage assembly frame 24 which is movable for effecting simultaneously shifting of all the cores 20 within their respective coils.

The core carriage assembly frame 24 is an L-shaped member which rides at one end thereof on a guide rod 25, which guide rod is rigidly secured to the front and rear plates of the supporting structure. The core carriage assembly frame is maintained in axial relation with the guide rod 25 by holes formed at opposing ends of the short leg of the L-shaped core carriage assembly frame. A selector shaft 26 is held in relation to the core carriage assembly frame by being positioned in an aperture disposed in the short leg of the L-shaped core carriage assembly frame with one end of said shaft being movably mounted in an aperture formed in the area 28 of the core carriage and protrudes beyond the side plate 14 and rides to and fro in the supporting structure via a slot 29 formed in the side plate 14. A ratchet stop wheel 30 and a ratchet turning wheel 31 are disposed on the shaft 26. Five stop lobes or dogs, four indicated by 32 and the fifth by 32' are equiangularly spaced in a spiral around the shaft 26, the four lobes 32 being used for engaging their respective limit nuts 33 for sequence operation, the lobe 32' being used with a limit nut 33' for manual tuning.

A ratchet stop finger 34 is pivotally mounted by a pin 35 on the supporting structure, and a spring 36 urges the ratchet stop finger 34 against the ratchet stop wheel 30 which rotates in the direction of arrow X, as shown. A ratchet turning finger 35' is pivoted on a pin 36' which is connected to the supporting structure, and engages the ratchet turning wheel 31 under influence of a spring 37. In the position shown in Fig. 2 the core carriage has been moved to the right almost as far as it will go and the turning finger 35' has rotated the wheel 31 and selector shaft 26 almost completely around to the next step of the selector sequence. A little further movement of the core carriage will cause the shaft to rotate far enough for the stop finger 34 to slip behind a ratchet tooth of the ratchet stop wheel 30, and keep the

shaft 26 from turning back to the last step position upon return of the core carriage.

The limit nuts 33 have their lower portions movably mounted in slots 40 formed in the base plate 16 of the supporting structure, while the upper portions of the limit nuts have shoulders 41 which are engageable by their respective lobes or dogs 32.

Positioning screws 43 have opposing ends pivotally mounted in the front and rear plates of the supporting structure and are held against longitudinal movement by collars 44 and 45 which are secured adjacent opposing ends of said positioning screws. A manual positioning screw 46 is similar to screws 43, and is disposed in relation to the supporting structure in the same manner as the positioning screws 43. A manual tuning knob 8 is used for manual tuning when the cam 32' is in engagement with its respective limit nut 33'. Limit nut 33' is disposed on the manual positioning screw 46 with one portion thereof protruding through a guide slot in the side plate 15 in a similar manner as the other limit nuts are guided in the slots 40 formed in the base plate.

There is a limit nut 33, a positioning screw 43, and a lobe 32 for each of four positions of the core carriage, representing a possibility of four selective radio stations which may be tuned in through sequence operation. A cylindrical stop 48 is disposed on the guide rod 25 to limit the extreme movement of the core carriage assembly frame 24 under influence of the retractile spring 49 connected between the front plate 12 and a pin 50 on the core carriage assembly frame 24, said retractile spring 49 constantly urging the core carriage toward the front plate 12 of the supporting structure so that the lobes 32 may engage their respective limit nuts 33, or the lobe 32' may engage the manual positioning screw nut 33'.

The cover plate 17 is fixedly secured on the upper edges of the front, rear and side plates by means of screws 47. A push button 51 secured to a push button arm 52, somewhat C-shaped in cross section, and slideable back and forth on a push button lever guide 53 secured to the cover plate 17. An operating lever 54 is pivoted to the push button lever 52 by a pivot pin 55. One end of the operating lever 54 is pivoted to the cover plate by a pivot pin 56. The opposite end of the operating lever is pivoted by a pin 57 to an operating link 58, the opposite end of said link being pivotally connected to the link stud 59 secured to the core carriage. The link stud is disposed to ride in the cover slot 60. Inward pressure on the push button in direction of the arrow Y will cause the core carriage to be moved rearwardly, and release of pressure on the push button will cause the retractile spring 49 to urge the push button and the core carriage to its forward position as limited by one of the cams on the cam shaft and its respective cam stop.

The solenoid 7 is shown by legend to be connected to a control circuit so that an electric push button may be connected in any convenient or conventional manner to operate the tuning mechanism in lieu of the manual push button 51.

In order to set-up or adjust the tuner for pre-selected signal reception, the operator sequentially operates the tuner until the desired stop lobe is in engagement with its complementary limit nut. Rotation of the particular limit nut positioning screw will then permit the core carriage to be moved until the desired station is properly tuned in. Thereafter that particular lobe and limit nut engagement, during sequential operation of the tuner, will cause the same station to be again tuned in.

From the foregoing presentation it will be seen that the tuning means may be varied in sequential operation for signal reception of preselected stations by successive actuations of the lobe carrying core carriage. Further, one of the lobes may be positioned by sequential operations of the core carriage, to engage a manually operable positioning screw for effecting tuning over a continuous range.

What is claimed is:

1. In a preselectable sequence tuner device: housing structure; a positionable tuning element slidably mounted with respect to the housing structure for controlling the tuning in accordance with its position; a rotatable selector shaft pivotally carried by the tuning element, and extending at an angle to the sliding direction of the tuning element, said shaft having a plurality of outwardly extending helically disposed stop lobes; a corresponding plurality of limit nuts individually held in the path of the respective stop lobes to limit the travel of the tuning element in one direction; sequence mechanism connected to the tuning element for moving it in the opposite direction in response to a sequence manipulation, and for automatically returning the element in said one direction when the sequence manipulation is completed; said sequence mechanism also including stepping elements connected for rotating the selector shaft one rotatory step during each to and fro movement of the tuning element to bring a different one of the lobes in position for engaging its limit nut to cause the tuning element to stop its return movement at predetermined positions; rotatable preselection screws each having longitudinally spaced portions pivotally held directly by said housing and threadedly carrying one of the limit nuts; and slots in the housing receiving said nuts and guiding them for threaded adjustment along their screws.

2. The combination as defined by claim 1 and including at least one additional slot in the housing for guiding the selector shaft and tuning element in their to and fro sequence movements with respect to the housing.
